United States Patent

Des. 241,842

Patented Oct. 12, 1976

241,842

FAUCET HANDLE BODY

Sidney J. Shames, 57 Holly Place, Briarcliff Manor, N.Y.
10510, and Harold Shames, 5 Agnes Circle, Ardsley,
N.Y. 10502

Filed Jan. 14, 1976, Ser. No. 649,038

Term of patent 14 years

Int. Cl. D23—01

U.S. Cl. D23—28

FIG. 1 is a side elevational view of a faucet handle body showing our new design;

FIG. 2 is a top plan view of the same;

FIG. 3 is a bottom plan view of the same; and

FIG. 4 is a fragmentary cross-sectional view taken substantially on line 4—4 of FIG. 2.

We claim:

The ornamental design for a faucet handle body, as shown.
